Des. 202,357
Patented Sept. 21, 1965

202,357

DUAL WORK TABLE OR SIMILAR ARTICLE

Douglas M. Sandefur, 6541 Brynurst,
Los Angeles 43, Calif.

Filed Feb. 3, 1964, Ser. No. 78,489

Term of patent 14 years

(Cl. D33—14)

FIG. 1.

FIG. 2.

FIG. 1 is a perspective view of a dual work table or similar article showing the top, one side and one end of my design, and

FIG. 2 is a perspective view showing the top, the other side and the other end thereof.

I claim:

The ornamental design for a dual work table or similar article, as shown.
